UNITED STATES PATENT OFFICE.

GUSTAV J. GRUENDLER, OF CLAYTON, MISSOURI.

REFRIGERATOR.

Application filed August 14, 1922. Serial No. 581,771.

To all whom it may concern:

Be it known that I, GUSTAV J. GRUENDLER, a citizen of the United States, residing in Clayton, in the county of St. Louis and 5 State of Missouri, have invented a new and useful Improvement in Refrigerators, of which the following is a full, clear, and exact specification, reference being had to the accompanying drawings, which form a 10 part thereof.

My invention relates to refrigerators and more particularly to refrigerators having an ice container arranged to be removed or 15 partially removed from the ice chamber therein when it is to be charged with ice.

It is a practice to have the ice container of a refrigerator arranged so that the container may be partially removed from the ice chamber when it is to be charged with 20 ice, and, when the container is removed from the ice chamber, as will be herein-after described, the warm outside air is admitted to the ice chamber of the refrigerator thereby causing the temperature there- 25 in to be raised with a resultant waste of ice to bring the air of the refrigerator back to its initial coldness. If a shield were mounted on the container and arranged to engage the marginal edges of the opening 30 through which the ice container is partially removed to be charged with ice, and it should be desired to completely remove the ice container from the refrigerator for the purpose of repairing or cleansing, a great 35 amount of work would be necessary to detach the shield from the ice container or to bring the shield into a position to be passed through the opening in the wall of the ice chamber.

40 The objects of my invention are to provide in a refrigerator having an ice container arranged to be partially removed therefrom when it is to be charged, a shield which will effectually prevent the inflow of 45 warm air or the outflow of cool air into or out of the refrigerator; to provide in a refrigerator a shield arranged to automatically close the opening through which the ice container is removed or partially re- 50 moved; and to provide a shield controlled by the movement of, but not attached to or mounted on, the ice container of a refrigerator so that said container may be easily and quickly removed from said refrigerator for the purpose of repairing or cleansing. 55

My invention is fully shown in the accompanying drawings wherein similar letters are used to designate similar parts. Fig. 1 is a sectional view of a refrigerator 60 embodying my invention, showing the ice container partially removed therefrom to be charged with ice; Fig. 2 is a sectional view showing the ice container in place in the ice chamber in the refrigerator; and 65 Fig. 3 is a sectional view along the line 3-3 in Fig. 1.

Referring to the figures, the refrigerator A has the ice chamber B therein. The ice container C is arranged to be moved into 70 and out of the ice chamber B through the opening D, preferably, in the front wall thereof. A door D', partially shown in Fig. 3, ordinarily closes the opening D when the ice container is in the ice chamber 75 B. The ice container C has on the lower portion of its sides the wheels E mounted on the axles F and arranged to roll on the tracks G which, as will be hereinafter described, are normally in place inside the ice 80 chamber B, as shown in Fig. 2, but which may be partially extended therefrom, as shown in Fig. 1. The shield J, preferably made of metal but which may be made of any rigid material, is swingably mounted 85 on the marginal portion of the front wall of the ice chamber B above the opening therein by means of the rod K, one end of which is carried in a socket in the end wall of the ice chamber B above the opening D 90 and the other end of which is carried by a boss on the opposite side of the opening, as shown in Fig. 3. The side wall of the ice chamber B adjacent to the opening D is provided with the vertical flanges L, ar- 95 ranged one on each side of the opening, which slant slightly inwardly from top to bottom, as shown in Fig. 2. The ice container C is provided at its top with the lugs M. The tracks G may be provided with 100 the connecting links H so that, when the ice container is partially removed from the ice chamber, the portions of the tracks G which are adapted to extend beyond the opening D may be positioned inside the 105 opening as shown in Fig. 2.

When the ice container is to be charged with ice, the door D' is opened and the outer ends of the tracks G are swung downwardly to extend from the refrigerator so 110 that they will be in alignment with those parts of the tracks which are fixed in the

ice chamber B. The ice container C is then moved outwardly through the opening D, the wheels E rolling along the track G. The shield J normally rests on the lugs M on the top of the ice container C and is thereby held away from the top of the ice container so as not to prevent the circulation of air into and out of said container. When, however, the ice container is moved outwardly the shield is allowed to swing downwardly as the ice container is moved, until it rests against the vertical flanges L, as shown in Figs. 1 and 3, and thus automatically closes the opening D. Since the flanges L slant inwardly from the top of the opening D, as hereinbefore described, the center of gravity of the shield will lie a sufficient distance outside of the plane of the contacting edges of the flanges L so that the weight of the shield will firmly hold it against the flanges. When the ice container has been charged it is pushed into the ice chamber B along the track G. The lugs M engage the shield J and force it upwardly as shown in Fig. 2. The extended portion of the track G is swung upwardly inside the opening D, as described, and the door D' is closed.

If the ice container is to be cleaned or repaired, it may be quickly and easily removed from the refrigerator by rolling it outwardly along the tracks G and then lifting it off said tracks, since it is not attached to any part of the refrigerator A.

It is obviously not my intention to limit my invention to the specific details of the construction shown in the drawings, since it may be readily seen that many of the details of construction, such as the form of the ice container, tracks, or the material of the shield J, may be varied without deviating from the spirit of my invention.

What I claim as new and desire to secure by Letters Patent, is:

1. In a refrigerator having an ice chamber therein with an opening in the wall thereof, an ice container adapted to be moved into and out of said chamber through said opening, flanges disposed adjacent the vertical sides of said opening and projecting inwardly from the wall of said chamber and having their inner edges inclined inwardly from top to bottom, and a shield swingably

mounted in said chamber above said opening and adapted to swing down into engagement with said inclined edges of said flanges when said container is moved out of said chamber.

2. In a refrigerator having an ice chamber therein with an opening in a vertical wall thereof, an ice container adapted to be moved into and out of said chamber through said opening, a shield swingably mounted above said opening and adapted to swing downwardly to close said opening and engage the sides thereof when said container is moved laterally out of said chamber, said shield and said sides of said opening being formed and arranged so that the center of gravity of said shield lies at a sufficient distance outside of the plane of the sides of said opening which are adapted to engage said shield whereby said shield will be automatically maintained in engagement with said sides when said container is out of said chamber.

3. In a refrigerator having an ice chamber therein with an opening in the wall thereof, an ice container adapted to be moved into and out of said chamber through said opening, a shield swingably mounted above said opening and adapted to automatically swing downwardly to close said opening when said container is moved out of said chamber, and means carried by said container whereby said shield is supported above and out of engagement with the top of said container when said container is in position in said chamber.

4. In a refrigerator having an ice chamber therein with an opening in the wall thereof, an ice container adapted to be moved into and out of said chamber through said opening, a shield swingably mounted on said wall above said opening and adapted to close said opening when said ice container is moved out of said chamber; and lugs projecting from the top of said container adapted to engage said shield when said container is moved into said chamber and adapted to hold said shield away from the top of said container when it is in said chamber.

In witness whereof I have signed my name to this specification.

GUSTAV J. GRUENDLER.
